CLAIM

We claim the ornamental design for knob for oven range, as shown and described.

DESCRIPTION

FIG. 1 is a front/right-side/top perspective view of a knob for oven range showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front/right-side/top perspective view which shows a knob for an oven range positioned on the front panel of an oven range.

The broken lines showing of the oven range is for illustrative purpose only and form no part of the claimed design.
